(57) **CLAIM**

The ornamental design for a specimen container, as substantially shown and described.

DESCRIPTION

FIG. 1 is a right side elevational view of the specimen container;

FIG. 2 is a left side elevational view thereof;

FIG. 3 is a front view of the specimen container;

FIG. 4 is a rear view of the specimen container;

FIG. 5 is a bottom plan view thereof;

FIG. 6 is a top plan view thereof; and,

FIG. 7 is a perspective view of the specimen container.

The broken line showing in FIGS. 1 through 6 are for illustrative purposes only and forms no part of the claimed design.
